RETAINING CLAMPS

Julien G. Bamberger, Milwaukee, Wis., assignor to B-T Company, Inc., Milwaukee, Wis., a corporation of Wisconsin

Application May 23, 1958, Serial No. 737,277

8 Claims. (Cl. 248—361)

This invention relates to retaining clamps, and more particularly to a retaining clamp for use with outboard motor remote fuel containers.

With the increased interest in boating in recent years, many new and useful improvements in outboard motors and boats have been developed to increase their efficiency and to enhance the comfort and enjoyment of the riders. One of the principal developments has been the introduction of remote fuel containers to replace the relatively small conventional engine fuel tanks. Such remote tanks permit the operation of a boat for an extended period, and eliminate the necessity for frequent refueling. An objection to the use of remote tanks, however, is that, rested on the bottom of the boat, such tanks have a tendency to bounce and vibrate and also to slide about on the floor, frequently knocking against the sides and seats of the boat to deface both the boat and tank. In addition, loose fuel tanks are inclined to slide on the bottom of a boat to spread oil and other messy and dangerously slippery substances about on said bottom. The general object of the present invention, therefore, is to provide a clamping device to anchor such remote fuel tanks and to prevent their undesired vibration and movement in a boat.

A further object of the present invention is to provide a clamp for outboard motor remote fuel tanks which may be easily and quickly installed on the bottom of a boat, and with which device a fuel tank may be locked securely in place or released in a matter of seconds.

A further object is to provide a positive locking clamp which may be manually operated or adjusted with a minimum of effort and without the necessity of additional tools or equipment.

A further object of the invention is to provide a locking device which will effectively anchor a remote fuel tank, thereby preventing such tank from causing injury to passengers or damage to the boat interior, and which device eliminates the necessity for makeshift protective padding on the boat.

A more specific object of the present invention is to provide a retaining clamp which, when three or more of the clamps are employed at spaced points around the sides of a fuel tank, will support said tank in an even plane elevated above the bottom of a boat.

A further object of the invention is to provide a clamp having novel means for preventing marring of the tank and for cushioning the clamped portion of the tank to insure against vibration noise.

A more specific object of the invention is to provide a fuel tank retaining clamp having a novel one-piece, resilient gripping member interposed between the tank base rim and clamp to prevent metal-to-metal contact.

A still further object of the invention is to provide a clamp having resilient jaw-protecting element which is formed of plastic or the like molded to provide a snap-in, snap-out fit with the tank base rim.

A still further object of the present invention is to

2

provide a fuel tank retaining clamp which is relatively small and inconspicuous.

Further objects are to provide a retaining clamp for outboard motor remote fuel tanks which is strong and durable, which is simple and inexpensive in construction, and which is well adapted for the purposes described.

With the above and other objects in view, the invention consists of the fuel tank retaining clamp, and all of its parts and combinations, as set forth in the claims, and all equivalents thereof.

In the drawing accompanying and forming a part of this specification, wherein the same reference characters designate the same parts in all of the views:

Fig. 1 is a perspective view of the clamp;

Fig. 2 is a vertical sectional view through the clamp, illustrating the clamp in initial engaging position with the base rim of a fuel container before the clamp has been tightened;

Fig. 3 is a plan view of the resilient gripping member alone; and

Fig. 4 is a fragmentary vertical sectional view of the clamp in firm, final engagement with the base rim of a fuel container.

Referring more particularly to the drawing, the fuel tank clamp includes a base member 10 which is generally L-shaped in cross-section, and which base includes a pair of opposed, laterally-projecting wings 11 having apertures 11' therethrough. The base member may be permanently secured to a boat bottom by means of bolts or the like projected through said apertures.

The horizontal portion 13 of said base member 10 preferably has a curved edge, as seen in Fig. 1, and a concave top surface 14 which slopes upwardly toward the vertical leg 15 of said base, there being a relatively narrow horizontal shelf 14' between said concave surface 14 and said vertical leg. A threaded hole 16 extends inwardly from said top face 14, and projects through the base at about a 45 degree angle from the vertical. Projecting upwardly from the outer edge of said top surface 14, and extending radially inwardly, is a lug 17, the function of which will be described hereinafter.

A top clamping plate 18 which is positioned on the base member 10 has a convex bottom conforming with the shape of the concave top surface 14 of said base member and is of progressively reduced thickness toward its upper edge, the latter being rounded as shown. Said top plate has a hole 19 therethrough in alignment with the threaded hole 16 in the base member, the inner end of said hole being enlarged to provide an internal spring shoulder 19' within said top plate. The outer edge of said top plate is provided with a slot 20, extending radially inwardly to a point spaced a short distance from the hole 19, to receive the aforementioned lug 17. The engagement of said lug 17 with said slot as illustrated in Fig. 1 prevents the rotatable movement of said top plate and maintains the same in proper position on the base.

A turn bolt 21, including a threaded shaft and an enlarged head 21', is projected through the hole 19 in the top plate 18, and is screwed into the aligned threaded hole 16 in the base 10, thereby adjustably joining said top plate and base member for clamping action. As will be seen in Fig. 2, a helical spring 22, surrounding said turn bolt shaft and abutting the shoulder 19' within said top plate, is interposed between said clamping and base members to hold the clamping plate snugly against the bolt head 21' and to prevent undesired downward sliding movement of said top clamping plate on the bolt. A washer 23 on the bolt is positioned over the opening in the outer face of said top plate to be engaged by the bolt head 21'.

Carried between the upper part of the top plate 18

and the base 10 is a resilient gripping member 24 which forms a very important component of the present invention. Said gripping member is generally Y-shaped in cross-section, as illustrated in Fig. 2, and comprises a stem 24' curved to match the concavity 14, having a bolt hole 29 therethrough (Fig. 3), the diameter of said hole being relatively large to permit some shifting of said gripping member on the bolt shaft. Diverging from the upper end of said stem 24' is a pair of arms 25 and 26 forming pincers, as will be more fully described hereinafter. Said gripping member is formed of resilient plastic, such as polyethylene, or other suitable material, and is rigid enough to retain its normal shape of Fig. 2 when there is no pressure thereon, but resilient enough that the arms will be pinched together when the top and base members are drawn together through the action of the turn bolt as in Fig. 4.

As illustrated in Figs. 2 and 4, the inner pincer arm 26 is shorter and is curved to fit against the adjacent upright portion 15 of the base. It is designed to engage the inner side of the base rim 28 of a remote fuel container, while the other, longer arm 25 engages the opposite or outer face of said bottom rim. Said pincer arm 25 has a transverse ridge 27 formed on and protruding from its inner face, intermediate its length. As will be seen, the vertical base rim 28 of the fuel tank is provided with an external shoulder 28' near its bottom edge formed by upturned marginal material of the tank bottom, which shoulder is engaged beneath the protruding ridge 27 when the gripping member is in pinching position of Fig. 4, thereby providing a locking means to prevent the accidental disengagement of the tank.

In use, three or more of the holding clamps may be permanently secured to the flooring of a boat by means of screws projected through the wing apertures 11', adjacent the spot the remote fuel tank is to be anchored. The heads 21' of the turn bolts are turned to partially withdraw the bolts, the springs 22 simultaneously separating the top clamping plates 18 from the base members 10. The vertical base rim 28 of a fuel tank is then lowered into the groove provided between said top plate and upright portion 15 of the base, and between the diverging arms 25 and 26 of the gripping member, as shown in Fig. 2. The weight of the fuel tank forces each resilient gripping member downwardly and firmly against its horizontal shelf 14' of the rigid base, as illustrated in Fig. 4, the enlarged nature of the hole 29, as hereinbefore described, permitting such shifting movement of the gripping members. During such movement, even if the clamps are not fully opened, the resilient nature of the gripping member 24 permits the shoulder 28' of the tank base rim to snap beneath the transverse rib 27 of the gripping member.

Finally, each bolt 21 is tightened to cause clamping. As a top clamping plate approaches its base its upper part engages the pincer arm 25 of the gripping member and forces the same inwardly toward the arm 26 and vertical leg 15 of the base member, squeezing the fuel tank rim 28 firmly between said arms. As will be seen in Fig. 4, when the top plate 18 is in clamping position, the pincer arms 25 and 26 assume a nearly vertical position, with the fuel tank base rim engaged securely therebetween, the protruding ridge 27 engaging above the shoulder 28' on the tank rim to provide a lock, and the bottom edge of the rim resting solidly on the horizontal shelf 14' of the base member.

When it is desired to release the clamps, as when the fuel tank is to be removed for refilling or storage, it is merely necessary to loosen the turn bolts and to lift up on the tank, which operation may be performed within a matter of seconds and without the necessity of special tools or equipment. Even if the clamps are not fully loosened, the resilient nature of the gripping members 24 permit the tank rim shoulders 28' to snap past the ribs 27 of the gripping members. As will be readily

appreciated, the novel clamp comprising the present invention provides a simple and efficient means for anchoring a remote fuel tank and for preventing such tank from spreading dirty water and oil around the bottom of the boat or causing injury to the passengers or marring of the boat interior or tank exterior.

Various changes and modifications may be made without departing from the spirit of the invention, and all of such changes are contemplated as may come within the scope of the claims.

What I claim is:

1. A retaining clamp comprising a pair of relatively movable rigid clamping members having an upwardly opening clamping recess therebetween, a gripping member of resilient material having spaced upwardly opening arms within said clamping recess which are so positioned therein as to be drawn together to clamp an object therebetween when said clamping members are drawn together, and means for clamping moving said clamping members.

2. A retaining clamp comprising a pair of relatively movable rigid clamping members having an upwardly opening clamping recess therebetween, a gripping member of resilient plastic material having spaced upwardly opening arms within said clamping recess which are so positioned therein as to be drawn together to clamp an object therebetween when said clamping members are drawn together, and means for clamping moving said clamping members, one of said gripping member arms having a horizontal locking ridge on its inner face.

3. A retaining clamp comprising: a rigid, L-shaped base; a movable top clamping plate adjacent said base; a gripping member carried between said base and clamping plate, said gripping member having a pair of upwardly opening arms; and means for drawing the base and top plate together, said clamping plate being so positioned with respect to said arms that an object inserted between said arms will be clamped.

4. A retaining clamp comprising: a rigid, L-shaped base having a threaded hole therethrough; a top clamping plate adjacent said base, said top plate having a hole therethrough in alignment with said threaded hole in the base; a resilient gripping member carried between said top plate and base and having a hole therethrough in alignment with said threaded hole, said gripping member having a pair of diverging resilient pincer arms; and a threaded bolt projected through the holes in said top plate and gripping member and screwed into the threaded base hole, whereby said base and top plate may be clampingly drawn together, said clamping plate being so positioned with respect to said pincer arms that an object inserted between said top plate and base, and between said resilient pincer arms will be resiliently clamped.

5. A retaining clamp for fuel containers of the type having a vertical base rim with a horizontal shoulder, which clamp comprises: an L-shaped base having an upright part and a horizontal part, the horizontal part of said base having a threaded hole; a top plate carried above said horizontal part and adjacent the vertical part of said base, said top plate having a hole therethrough in alignment with said threaded hole of the base; a resilient gripping member carried between said top plate and base and having a hole therethrough in alignment with said threaded hole, and having a pair of upwardly opening pincer arms between said top plate and the adjacent vertical part of the base, one of said pincer arms having a transverse ridge on the inner surface thereof; and a threaded bolt projected through the holes in said top plate and gripping member and screwed into the threaded base hole to adjustably join said top plate and base whereby said top plate and base may be drawn together, and whereby the bottom rim of a fuel container inserted between said top plate and base, and between said diverging pincer arms will be resiliently clamped between said pincer arms, said pro-

truding pincer arm ridge being positioned to engage above the rim shoulder.

6. A retaining clamp for fuel containers of the type having a vertical base rim with a horizontal shoulder, which clamp comprises: a base; a top plate movably carried adjacent said base; a pair of upwardly opening resilient pincer arms carried between said base and top plate, one of said arms having a protrusion on the inner surface thereof; and means for drawing the base and top plate together, whereby the bottom rim of a fuel container inserted between said base and top plate, and between said pincer arms, will be resiliently clamped between said pincer arms, said pincer arm protrusion being positioned to engage above the rim shoulder.

7. A retaining clamp for fuel containers of the type having a vertical base rim with a horizontal shoulder, which clamp comprises: a base; a top plate movably carried adjacent said base; spring means between said top plate and base normally maintaining the same in spaced relationship; a pair of upwardly opening resilient pincer arms carried between said base and top plate, one of said arms having a protrusion formed on the inner surface thereof; and means for drawing the base and top plate together against the action of said spring means, whereby the bottom rim of a fuel container inserted between said base and top plate, and between said pincer arms, will be resiliently clamped between said pincer arms, said pincer arm protrusion being positioned to engage above the rim shoulder.

8. A retaining clamp for fuel containers of the type having a vertical base rim with a horizontal shoulder,

which clamp comprises: an L-shaped base having a horizontal part and an upright part, the horizontal part of said base having a threaded hole; a top plate carried above said horizontal part and adjacent the vertical part of said base, said top plate having a hole therethrough in alignment with said threaded hole of the base; spring means between said top plate and base normally maintaining the same in spaced relationship; a resilient gripping member carried between said top plate and base, said gripping member having a hole therethrough in alignment with said threaded hole of the base, and said gripping member having a pair of diverging upwardly opening pincer arms between said top plate and the adjacent vertical part of the base, one of said pincer arms having a protruding ridge formed on the inner surface thereof; and a threaded bolt projected through the holes in said top plate and gripping members and screwed into the threaded base hole to adjustably join said top plate and base, whereby said top plate and base may be drawn together against the action of said spring means, and whereby the bottom rim of a fuel container inserted between said top plate and base, and between said diverging pincer arms will be resiliently clamped between said pincer arms, the protruding pincer arm ridge being positioned to engage the rim shoulder.
